US0D1073090S

(12) **United States Design Patent** (10) **Patent No.:** **US D1,073,090 S**
(45) **Date of Patent:** **** Apr. 29, 2025**

(54) **ORTHOPAEDIC DEVICE**

(71) Applicant: **Guy Solan**, Surrey (GB)

(72) Inventor: **Guy Solan**, Surrey (GB)

(**) Term: **15 Years**

(21) Appl. No.: **29/818,255**

(22) Filed: **Dec. 7, 2021**

(30) **Foreign Application Priority Data**

Jun. 9, 2021 (GB) 6141599

(51) **LOC (15) Cl.** **24-04**

(52) **U.S. Cl.**

USPC **D24/192**

(58) **Field of Classification Search**

(57)

CLAIM

The ornamental design for an orthopaedic device as shown and described.

DESCRIPTION

FIG. 1 is a top plan view of the orthopaedic device showing the claimed design;

FIG. 2 is a right side view thereof;

FIG. 3 is a front view thereof;

FIG. 4 is a left side view thereof; and,

FIG. 5 is a front perspective view thereof.

1 Claim, 5 Drawing Sheets
